UNITED STATES PATENT OFFICE

140,477

DESIGN FOR A JACKET

Hans Herrmann, Chicago, Ill.

Application December 4, 1944, Serial No. 116,700

Term of patent 7 years

(Cl. D3—4)

To all whom it may concern:

Be it known that I, Hans Herrmann, a citizen of the United States and a resident of Chicago, in the county of Cook and State of Illinois, have invented a new, original, and ornamental Design for a Jacket, of which the following is a specification, reference being had to the accompanying drawing, forming part thereof, in which

Fig. 1 is a front view of a jacket showing my new design;

Fig. 2 is a rear view of the same; and

Fig. 3 is a detail view showing the design of the border.

I claim:

The ornamental design for a jacket, as shown.
HANS HERRMANN.
